A. K. SIMMONS

RAILWAY CAR

Filed Jan. 13, 1922

UNITED STATES PATENT OFFICE.

ALBA K. SIMMONS, OF ROANOKE, VIRGINIA, ASSIGNOR TO B. W. KADEL, OF BALTIMORE, MARYLAND, AND JOHN A. PILCHER, OF ROANOKE, VIRGINIA.

RAILWAY CAR.

Application filed January 13, 1922. Serial No. 529,014.

To all whom it may concern:

Be it known that I, ALBA K. SIMMONS, a citizen of the United States, residing at Roanoke, in the county of Roanoke and 5 State of Virginia, have invented certain new and useful Improvements in Railway Cars; and I do hereby declare the following to be a full, clear, and exact description of the invention, such as will enable others skilled in 10 the art to which it appertains to make and use the same.

This invention relates to a door-securing and door-closing mechanism for railway cars or the like, and has among its objects 15 to provide means for supporting the door of a railway car in partly closed position, and additional means for supporting it in fully closed position. Another object is to provide in combination with a car door, removable means for forcing the door from a partly closed to a fully closed position. Another object is to provide a simple and economical form of door supporting mechanism not liable to be injured in ordinary service. 20 Other incidental objects will appear as the description of the invention is set forth.

In the accompanying drawings, which show a preferred embodiment of the invention, Figure 1 is a fragmental side elevational view of a railway car, having doors with a supporting and closing mechanism constructed in accordance with the principles of the present invention. Figure 2 is a transverse vertical section taken through the 35 same, substantially on the irregular line 2—2—2—2 of Figure 1. Figure 3 is a horizontal sectional view taken substantially on the irregular line 3—3—3—3—3—3 of Figure 1. Figure 4 is a detached view of the 40 preliminary supporting hook as used in the present embodiment of the invention.

Referring now to the embodiment shown in these drawings, the car side plate is indicated by the numeral 1. To the lower edge 45 of the same is secured a reinforcing angle iron 2, having its upright or vertical leg 3 disposed on the inner face of the car side and its horizontal leg 4 turned toward the outside of the car and extending outwardly 50 beneath the side plate 1. Rivets such as 5 may be utilized for securing the angle iron to the car side.

A portion of the car floor is shown at 6. Hinged to the floor by means of co-operating 55 body and door hinges 7 and 8 is a door 9.

The numeral 10 denotes the hinge pintle. A fragment of a companion door 11 is also shown, these doors being, in the present embodiment, duplicates of each other and arranged as a pair, hinged along their remote 60 edges to the car body and with their free edges adjacent. This is an arrangement of doors frequently used, but it is to be understood that the invention is applicable either in whole or in part, to any other door arrangement, either where they occur singly 65 or in pairs.

The doors are held in closed positions by suitable door supporting members, such as the hooks 12, which have supporting ledges 70 31 arranged to seat beneath cooperatively formed portions of the doors. These hooks are pivoted to the car body through the medium of a suitable bracket 13. This bracket 13 lies directly against the car side 1, and has 75 spools or bosses attached to it, over which the pierced upper ends of the hooks 12 are placed. These spools 14 are suitably pierced for receiving attaching rivets 15, which pass through the spools and through aligned 80 openings in the car side, and also through aligned openings in an outer covering plate 16, which overlies the bracket 13 and the hooks. A collar such as 17 is preferably 85 provided upon each spool to position the hook 12 so that it will swing freely along the outermost edge of the leg 4 of the angle 2.

Positioned also between the bracket 13 and the plate 16, and rotatably mounted 90 upon similar spools 30 are eccentrics or cams 18, which are arranged in the customary manner to retain the hooks in their closed positions so as to prevent their accidental displacement from engagement with the doors. Similar collars 17 are provided for the spools 30 and similar attaching rivets 19 pass through the spools 30 at the pivots of the cams 18.

It will be understood that sufficient clearance is provided between the faces of the collars 17 and the inner face of the plate 16 to allow freedom of movement of the hooks and the cams about their respective pivot points. At the same time the hooks and 105 cams are held in alignment between the collars 17 and plate 16.

The door plates extend outwardly to near the outer edge of the horizontal flange 4 of the angle 2, so that the hooks 12 swing clear 110

of the outer ends of the door plate. Each door is preferably provided with a reinforcing angle iron 20, disposed along the free edge of the door, and extending slightly beyond the outer edge of the door plates, and outside the edge of the flange 4 of the angle 2. The ends of these angle irons, which are securely attached to the door plates, form seats for the ledges 31 of the hooks. The backs of the angle irons 20 of the companion doors are turned toward each other, or in other words, with the horizontal flanges thereof extending toward the respective door pintles. The hooks seat beneath the horizontal legs of the angles 20, and swing away from each other for releasing.

Each hook is preferably provided with an approach portion 21, so arranged that when the doors are lifted up, the contacting portion of the angle 20 will, by striking the sloping face 21 of the hook, cause said hook to swing backward ready for eventually dropping into position beneath the horizontal leg of the angle 20, when the door has been lifted a proper amount. The inward swing of the hook when the door is open may be limited by stops such as 22 provided upon the cover plate 16.

It will be understood that the ledges 31 of the hooks 12 are intended to support the doors independently in fully closed positions. This is a construction in more or less use today on railway cars. It sometimes happens, however, that doors of this character cannot be readily closed to the final position, such as indicated to the left of Figure 1, due to deformation of parts or to interference of foreign material lodged at some critical point, it being the general practice in this character of construction to lift the doors by hand. It is generally possible, however, to partly close the doors by hand, and accordingly one of the principal objects of the present invention is to provide a preliminary door support, to which either of the doors may be lifted and upon which it may be positioned before attempting to lift the door to and lock it in its final or fully closed position.

To this end, there is provided in the present embodiment of the invention, a preliminary closing hook 23, which is loosely hinged upon the bracket 13. This hook is arranged to seat beneath an edge of either door plate and to hold either door, as shown in the right hand portion of Figure 1, in a position not fully closed. This hook is preferably mounted upon the bracket 13 and may be supported therefrom upon a spool 32 similar to those provided for the pivot points above mentioned, except that ribs 33 are provided upon the top of the spool for retaining the hook 23 in proper position longitudinally of the spool. The hook in the present embodiment is so formed as to

accommodate either of the two doors. To this end, it is formed of a round bar of steel, welded into loop form, and then bent into hook form, with a lower approach portion 24 which causes the hook 23 to be swung outwardly, or away from the car side, when either of the doors is lifted up. When the doors are to be dropped from fully closed position, the hook 23 may be swung back out of the path of the doors and may be held back by the insertion of a small block between it and the edge of the angle iron 2, or the hook 23 may be lifted and positioned outside of the outer one of the ribs 33, thereby locating the hook 23 in a new position of swing where it will fall by gravity into a position to clear the doors when they are dropped. When it is desired to temporarily support the doors upon the hook 23 it will be shifted inwardly into the operative position shown in the drawings. This hook is formed of lighter material than the main hook 12 inasmuch as it supports the unloaded door only, whereas the main hook is subjected to the weight of the lading above the door.

In order that this hook 23 may not be swung out of position longitudinally along the side of the car when the weight of a door is supported upon it, the outstanding leg 4 of the angle 2 is coped out as at 25, thereby forming a cavity in the flanged portion of this angle for the reception of the hook 23. Any tendency of the hook to move longitudinally of the car will be arrested by its coming into contact with a shoulder, such as 26, defining the end of this cut in the angle leg.

Another object of the invention being to provide means, associated with the car body and the door, for forcibly lifting the door from a preliminary position as just described to its final position, I have provided a removable lever 34, which is shown in the attached drawings. This lever is arranged to have its inner end 35 seat upon the upper surface of the outstanding leg 4 of the angle 2, just above one or the other of the door angles 20. Pivoted to this lever at 27 is a depending hook 28 which has an inturned point 29 so arranged that when the end of the lever is in position on the flange of the angle 2, the point 29 of this hook will drop into position beneath the down standing leg of the corresponding door angle 20. By now lifting up on the outer end of the lever, the door may be forcibly lifted from its preliminary position on the hook 23 to a final or fully closed position where the ledge 31 of the hook 12 will be seated beneath the horizontal flange of the door angle 20. The means for forcibly moving the door from its preliminary position to its fully closed position being detachable and separate from the door-supporting mechanism, it will be

seen that one of the levers will serve an entire unloading station instead of supplying separate closing means for each individual car.

- 5 The horizontal flange portion of the angle iron 20 is preferably of greater length than the remainder of the angle iron, and this end of the flange may be turned down at the end of the angle and outside of the hook seat 10 so as to form a stop for the hook and thereby limit shifting of the door in one direction as well as prevent said hook from coming off its seat from accidental movement of the hook longitudinally of the door. The end 15 of the horizontal flange of the angle 20 that engages the supporting ledge 31 of the hook being bent substantially at right angles to its normal plane constitutes an economical means for providing a supporting surface 20 for the hook, without the employment of a separate bracket or rivets, both of which add to the cost and weight of such devices.

It will be seen that either door may be rested on the preliminary hook and the lever 25 may be moved from one door angle to the other to force either door up into final position. The entire arrangement is not only inexpensive and compact, but is also sturdy and of a character not readily damaged in 30 the ordinary course of service. The doors may be quickly dropped and forcibly closed and when once closed they cannot accidentally open. Furthermore, no previous experience or special instruction is necessary 35 for the workmen who unload such cars as the simplicity of the arrangement renders it readily understandable to the unskilled workman.

I have thus described a preferred embodiment of my invention. Other embodiments are contemplated within the scope of the appended claims without departing from the spirit of the invention.

What is claimed is:

- 45 1. A railway car having a door, a door-securing member carried by the car and arranged to support the door in fully closed position, and additional door-supporting means pivotally mounted upon the car for supporting the door in a partly closed position.

55 2. A railway car having a door, a door-securing mechanism carried by the car and arranged to support the door in fully closed position, and additional door-supporting means pivotally associated with the first mentioned door-securing mechanism for supporting the door in a partly closed position.

60 3. A railway car having a door, a door-securing member carried by the car and arranged to support the door in fully closed position, additional door-supporting means carried by the car for supporting the door in a partly closed preliminary position, a 65 relatively fixed portion of the car body and

a portion of the door being formed and arranged to accommodate detachable means operable therebetween for forcing the door from the preliminary position to the fully closed position.

70 4. A railway car having a door, a door-securing member pivoted to the car and having a ledge arranged to engage a portion of the door and to sustain the door in fully closed position, additional door-supporting means also pivoted to the car and having a ledge arranged to engage a portion of the door and to sustain the door in partially closed position, a relatively fixed portion of the car body and a portion of the door being 75 formed and arranged to accommodate a removable lever operable therebetween for forcing the door from partially closed to fully closed position.

80 5. A railway car having a door, a hook pivoted to the car body and arranged to engage a portion of the door and to support the same in fully closed position, and an additional hook also pivoted to the car body and arranged to engage a portion of the door and to support the same in partly closed position, a relatively fixed portion of the car 85 and a portion of the door being formed and arranged to accommodate means reacting therebetween for forcibly moving the door 90 from its partly closed to its fully closed position.

95 6. A railway car having a door, a main hook pivoted to the car body and arranged to engage a portion of the door and to support it in fully closed position, and under full load, an auxiliary hook also pivoted to the car body and arranged to engage a portion of the door and to support it in partially closed position, the said auxiliary hook 100 being of lighter construction than the main hook, adjacent parts of the car and the door being arranged to receive means for forcing the door from its partly closed position to its fully closed position.

105 7. A railway car having a door, a plurality of hooks pivoted to the car body and respectively adapted to support the door in different position, adjacent parts of the car and door being arranged to receive removable means independent of the hooks and reacting between the car and the door for forcing the door from one position to another.

110 8. A railway car having a door, a main hook pivoted to the car body and arranged to swing in a plane into engagement with a portion of the door and to support the door in fully closed position, and an auxiliary hook also pivoted to the car and arranged to swing in another plane into engagement with a different portion of the door and to support the door in partly closed position.

115 9. A railway car having a door, a bracket affixed to the car body a main hook pivoted 120

upon the bracket and arranged to support the door in fully closed position, an auxiliary hook also pivoted upon the bracket and arranged to support the door in partly closed position, adjacent parts of the car and door being arranged to receive means for forcibly lifting the door from one of said positions to the other.

10. A railway car having a door, a hook pivotally connected to the car body, an angle iron connected to the door and arranged for cooperation with the said hook to hold the door in closed position, a portion of the angle iron being extended beyond the position

15. of the hook and being there deformed into a position parallel with the swing of the hook in such manner as to form a stop for limiting movement of said hook longitudinally of the door.

20. 11. A railway car having a pair of doors hinged to the car body and arranged with their free edges adjacent, a main supporting member for each door, the same being pivoted to the car body, and arranged to support 25 the respective doors in fully closed positions, and a preliminary supporting member carried by the car body and arranged to support either of the two doors in partly closed position.

25. 12. A railway car having a door hinged to the car body, a hook pivoted to the car body and arranged to swing in a plane parallel with the side of the car and to support the door in fully closed position, an auxiliary hook also pivoted to the car body and arranged to swing in a plane at right angles to the side of the car, and means affixed to the car body for holding the hooks against displacement from their respective planes of 40 swing.

30. 13. A railway car having a door and a door securing mechanism, said door securing mechanism including a hook spaced from the car side, and including also a bracket having 45 a base arranged for attachment to the car side, a spool attached to the base of the bracket, a stop for the hook, the same being arranged outwardly of the base of the bracket and inwardly from the outermost 50 end of the spool, said stop being adapted to limit movement of the hook axially of the spool toward the car side, and a plate overlying the spool, the hook being pivoted upon the spool and operating between the said 55 stop and the plate.

35. 14. A railway car having a hinged door with a stiffening member attached thereto extending outwardly beyond an edge of the door, and a door-supporting hook pivoted 60 to the car body in position to engage the end of said stiffening member, the said stiffening member being formed of an angular section having two flanges, the said hook being arranged to seat beneath one flange 65 thereof and one of said flanges being bent

out of its normal plane to overlie the side of the hook.

15. A railway car having a hinged door with a stiffening member attached thereto extending outwardly beyond an edge of the door, and a door-supporting hook pivoted to the car body in position to engage the end of said stiffening member, the said stiffening member being formed of an angular section having two flanges, the said hook 75 being arranged to seat beneath one flange thereof and said flange being bent substantially at right angles out of its normal plane in the vicinity of the hook to form a contacting surface for the hook. 80

16. A railway car having a hinged door with a stiffening member attached thereto extending outwardly beyond an edge of the door, and a door-supporting hook pivoted to the car body in position to engage the 85 end of said stiffening member, the said stiffening member being formed of an angular section having two flanges, the said hook being arranged to seat under the said stiffening member, and one of said flanges being 90 bent out of the normal plane thereof, said bent portion being adapted to engage the said hook in the supporting position of the latter.

17. A railway car having a plurality of 95 hinged doors located adjacent each other, means pivotally associated between the car body and a plurality of the doors for supporting either of said doors in a partly closed position, and independent means pivotally associated between the car body and each door for supporting the doors individually and independently of each other in fully closed positions. 100

18. A railway car having a hinged door, 105 a latch pivotally associated between the car body and the door and arranged to support the door in a partly closed position, and an additional latch also pivotally associated between the car body and the door and arranged to support the door in a fully closed position, the first mentioned latch being shiftable bodily from one position to another and being so arranged with respect to the door that in one position it will fall by gravity into supporting engagement with the door and when in the other position it will lie outside of the path of swing of the door. 110 115

19. A railway car having a hinged door, 120 a door supporting arm attached thereto, said arm extending outwardly beyond an edge of the said door, and a door supporting hook pivoted to the car body in position to engage the end of the said arm, the said 125 arm being formed of a rolled section and having a portion thereof bent out of its normal plane to overlie the side of the hook to limit endwise movement of the door in one direction. 130

20. A railway car having a hinged door, and means for supporting said door in closed position involving two relatively movable members one of which is mounted on the car body and the other upon said door, one of said members constituting a hook and the other of said members providing a seat engageable by said hook when the door is in closed position, the said member by which the seat for said hook is provided being formed with a bent portion projecting away from said seat at an angle to the plane thereof and overlapping the side of said hook member when the latter is in door supporting relation to said seat, thereby limiting endwise movement of said door in one direction. 25
21. In a car door arrangement, the combination with a drop door hinged to the car body, of means for supporting said door in partly closed position, and means for supporting said door in fully closed position, said first named means including a pivoted member operatively interposed between said door and the car body, and said means for supporting said door in fully closed position involving a pivoted member operatively interposed between said door and the car body and movable with respect to said pivoted member first named. 30
22. In a car door arrangement, the combination with a drop door hinged to the car body, of a plurality of independently movable pivoted members either of which is adapted to be operatively interposed between said door and the car body to support said door, one of said pivoted members being adapted to assume a position for supporting said door in partly closed position and the other of said pivoted members being adapted to engage and support said door when the latter is in fully closed position, and both of said pivoted members being required to swing to unlocked positions to permit said door to swing to open position. 35 40 45

In testimony whereof I affix my signature.

ALBA K. SIMMONS.
